ABSTRACT

Disclosed is a power unit and engine wherein reciprocal motion of piston means are transformed into rotary motion of an output shaft without the aid of cranks and connecting rods. More particularly is disclosed a power

unit which includes at least one cylinder piston assembly and an axially aligned rotor cam means connected to a drive shaft which means, in operative association with the piston which is guided for reciprocation only, transforms the reciprocal motion of the piston into rotary motion of the drive shaft. In the preferred form there is employed two substantially identical but opposed cylinder, piston and rotor assemblies in axial alignment, with means associated with the opposed pistons for causing them to reciprocate in unison. The opposed rotor means are connected to a unit shaft and are hollow, cylindrical rotors having annular cam surface means which in operative association with piston cam rollers transforms the reciprocal motion of the pistons into rotary motion of the unit shaft. The means for causing said pistons to reciprocate in unison comprises rod means between the pistons and slidably received within a bore through the unit shaft. The length of the rod means is such to control the separations of said pistons whereby a power stroke of one piston effects the return stroke of the opposed piston and maintains the cam rollers of the opposed piston in disengagement from the cam surface means of its associated rotor means during its return stroke. In addition is disclosed a steam engine with the operative association of a plurality of these power units about a common, central output drive shaft. Timed valve means control the flow of steam through the cylinders of the units and a mechanism is provided for advancing the valve means in response to an increase in rotation of the central drive shaft. Further a lubrication system is disclosed for such engine. When a power unit is adapted in an internal combustion engine, there is provided a power storage piston which stores energy from the initial impingement caused by firing the working fluid and which subsequently releases substantially all the stored energy during the power stroke of the piston whereby the sudden build-up of stress in the cam engaging surfaces is reduced.

ENGINE POWER UNIT

FIELD OF THE INVENTION

This invention relates to power units and more particularly to improvements in positive displacement power units wherein reciprocal motion of a piston is mechanically converted into rotary motion, and vice versa, without the use of cranks, connecting rods, and the like. Further, this invention relates to the operative association of at least two such units in an engine with suitable rotary valve, and valve advance means for controlling the flow of a working fluid to the units and with suitable lubrication means for the engine.

BACKGROUND

Modern day positive displacement power units conventionally employ a crankshaft and connecting rod to convert the reciprocating motion of the piston to rotary motion of a shaft, and vice versa. The internal combustion engine, commonly found in today's automobiles, and the steam engine found in several of today's power plants are examples of engines employing this type of conventional power unit construction.

It is well known that crankshafts and connecting rods contribute to problems in the dynamic balancing of modern day engines. In addition, the use of a crank creates side thrust producing ovalization of the cylinder and serious wear on the piston and results in a loss of power transmitted causing decreased efficiency. Moreover, power units employing cranks and connecting rods to convert reciprocal motion into rotary motion and vice versa are relatively large and heavy as a result of the space required to accommodate the translational movement of the connecting rod following the circle of the crank.

In my invention as disclosed in U.S. Pat. No. 3,219,669 granted Apr. 21, 1964 I disclose a basic power unit wherein rotary motion is mechanically converted into positive displacement without the use of a crankshaft mechanism. My power unit as disclosed in that patent overcomes the disadvantages of prior art units by transmitting power through a wedging or camming action between substantially in line stators and rotating, reciprocating pistons. No crankshaft mechanism is employed and the unit is substantially self-balanced with little uneven wear resulting in the walls of the cylinders.

It will be appreciated however that in the power unit as disclosed in that patent, excessive heat is developed as a result of friction between the rotating wedge or cam surfaces of the piston and the stationary wedge or cam surfaces of the stator. In addition, heat is developed within the cylinders as a result of rotation of the pistons therein and such heat is not readily dissipated from the unit. Heat would particularly be a problem if a plurality of units as disclosed in that patent were coupled within a larger housing to form a composite power unit or engine.

OBJECTS

My present invention uniquely overcomes the disadvantages of the prior art power units utilizing crankshaft mechanisms and of my prior device in providing a reliable, durable power unit which is relatively inexpensive, is substantially self-balanced and has significantly less frictionally engaging surfaces and accordingly heat dissipation problems.

It is an object of this invention to provide an improved power unit wherein power is transmitted from a reciprocating member to a rotary output member, without the use of cranks and connecting rods.

5 It is a further object of this invention to provide an improved power unit wherein the linear displacement of a non-rotating piston means on its power stroke is transformed into rotary output motion through a wedging or camming action between the piston means and a hollow, cylindrical, axially aligned rotor means, with little friction between engaging surfaces.

10 It is a still further object of this invention to provide a power unit wherein two such piston means and rotor means are in axially opposed relationship and associated in such manner that the linear displacement of each piston means on its respective power stroke is transformed into a rotary output while such piston displacement effects the return stroke of the other piston means, the pistons thereby reciprocating substantially in unison.

15 It is still a further object of this invention to provide a power unit including opposed and axially aligned piston and cylinder means and interposed power transmitting rotor means wherein reciprocal non-rotary motion of each opposed piston means in its respective cylinder is transformed into rotary motion of said power transmitting rotor means, the rotor means consisting of opposed angularly offset cam surface means each of which, in cooperation with operatively associated cam means of the piston means causes rotation of said rotor means, and the opposed piston means operatively associated for reciprocation in unison whereby the power stroke of each piston means effects the return stroke of the other piston means without engagement between the cam means of the returning piston means and its associated cam surface means, thereby periodically relieving the stress due to contact between the piston means and cam surface means and permitting a cam surface profile with a longer power stroke surface which enhances net power output of the unit.

20 25 30 35 40 45 It is a further object of this invention to provide in a power unit, a power storage piston wherein a part of the energy resulting from the impingement of an active working fluid on the piston is stored therein during the initial part of its power stroke and subsequently substantially released during the latter part of its power stroke.

50 It is a still further object of this invention to provide an engine embodying a plurality of such power units about a central drive shaft, operatively associated through suitable gearing and valve control means.

55 It is yet a further object of this invention to provide a dynamically balanced steam engine embodying a plurality of my power units operatively associated about a common central drive shaft for transmission of power between a working fluid input and rotary output of the common drive shaft with valve control means for controlling in suitable timed relation the flow of working fluid to the plurality of power units and lubrication means suitably lubricating the reciprocating and rotating elements.

60 65 It is yet a further object of this invention to provide in such a steam engine having rotary valves, a valve advance mechanism which is simple in construction yet reliable in performance and consists of means operatively connected to said drive shaft to counterrotate in

response to the speed of said shaft the valve sleeve means housing the rotary valves.

It is a still further object of this invention to provide in such a steam engine a reliable lubrication system which effects continuous lubrication of all reciprocating and rotary elements of the engine.

Other objects and advantages of this invention will become more apparent upon a full appreciation of the drawings attached hereto, illustrating, in conjunction with the following description, the preferred forms of my invention.

FIG. 1 is an elevational view partially in section of an internal combustion engine in which my power unit is embodied;

FIG. 2 is a sectional plan view of the engine of FIG. 1 and shows in section the piston and rotor means and shows further a power take off shaft;

FIG. 3 is a sectional view taken along lines 3—3 of FIG. 2;

FIG. 4 is a sectional view taken along line 4—4 of FIG. 2;

FIG. 5 is an enlarged view of part of FIG. 2 taken within line 5—5 thereof;

FIG. 6 is an enlarged view of part of FIG. 3 taken within line 6—6 thereof;

FIG. 7 is an exploded perspective view of the power transmitting elements in the engine of FIG. 1;

FIG. 8 is a plane developed view illustrating schematically the rotor means and piston drive rollers of the power transmitting elements in the engine of FIG. 1, with FIGS. 5 & 6;

FIG. 9 is an elevational view of a steam engine embodying a plurality of my power units;

FIG. 10 is a left end view of the engine in FIG. 9;

FIG. 11 is a sectional view taken along line 11—11 of FIG. 10 showing generally a single power unit in the steam engine;

FIG. 12 is a sectional view taken along line 12—12 of FIG. 10 showing two diametrically opposite power units in the engine of FIG. 9, one of the units only being shown in full section;

FIG. 13 is a vertical, sectional view taken along line 13—13 of FIG. 9 showing generally the main gear assembly for the steam engine, with FIG. 10;

FIG. 14 is a sectional view taken along line 14—14 of FIG. 9 showing, in section, the cam rotor elements of the steam engine;

FIG. 15 is a broken sectional view taken substantially along line 15—15 of FIG. 9 showing, in part, the piston and cylinder units and cover plate of the steam engine;

FIG. 16 is a sectional view taken along line 16—16 of FIG. 9 showing in part cylinders and a cylinder head of the steam engine;

FIG. 17 is a vertical sectional view taken along line 17—17 of FIG. 9 showing the valves and valve control mechanism in the left end cylinder head of the steam engine;

FIG. 18 is a plan view in section, taken along line 18—18 of FIG. 9 showing the valves and valve control mechanism;

FIG. 19 is a partial sectional view of a cylinder head valve sleeve bore taken along line 19—19 of FIG. 10;

FIG. 20 is an end view of a valve sleeve as employed in the engine;

FIG. 21 is a partial sectional view of the valve sleeve of FIG. 20 taken along line 21—21 thereof;

FIG. 22 is an end view of the other valve sleeve as employed in the engine;

FIG. 23 is a side view of a rotary valve of the steam engine as employed in the cylinder head shown in FIG. 5 18 and in a valve sleeve as shown in FIG. 21;

FIG. 24 is a sectional view along line 24—24 of FIG. 19;

FIG. 25 is a sectional view of the rotary valve as employed in the right end cylinder head, as viewed in FIG. 10 18;

FIGS. 26—29 are sectional views taken generally along lines 26—26, 27—27, 28—28, and 29—29 of FIG. 18 respectively, showing in part and schematically, the valve mechanisms;

FIG. 30 is a table showing a timing of the valves;

FIG. 31 is a bottom sectional view taken along line 31—31 of FIG. 10 showing the valve advance mechanism and oil return passages for the steam engines; and

FIG. 32 is a vertical sectional view taken along line 32—32 of FIG. 10 showing in part the lubrication conduit system for the steam engine.

BASIC POWER UNIT

Now with reference to the drawings and particularly FIG. 1 through 8, there is illustrated my basic power unit 10 employed in a two cycle internal combustion engine. It will be appreciated that although the illustrated engine is a gas engine my invention is not limited to that particular type of engine but is also adaptable for application upon a diesel engine or steam engine.

Power unit 10 as viewed in FIG. 1 consists of a pair of opposed cylinder, piston and rotor units 12, 12a mounted in axially alignment and operatively associated by means of common rotatable shaft 14. Units 12, 35 12a are mounted on base 15 through screws 16 and upstanding supports 17, 17a. Base 15 may be secured to a suitable foundation support 18 by means of bolts 19.

It will be appreciated from reviewing the drawings that units 12, 12a are mirror images of each other and may be described as opposing "left" and "right" units. Accordingly, the letter "a" is used to designate those elements of the right unit or unit 12a which have counterparts in the left unit, or unit 12.

Units 12, 12a include identically constructed and opposed housings 20, 20a having outer surfaces 21, 21a and inner surfaces 22, 22a. Bolts 23 secure cylinder heads 24, 24a to housings 20, 20a with the inner surface of cylinder head flanges 25, 25a respectively abutting outer housing surfaces 21, 21a. Any suitable seal such as an aluminum seal may be used in securing the respective cylinder heads to the housings.

Housings 20, 20a have respective internal rotor bores 26, 26a of uniform diameter extending inwardly from surfaces 21, 21a to internal housing flanges 28, 28a respectively. Slotted cylindrical skirt 30, 30a of cylinder heads 24, 24a extend into rotor bores 26, 26a and are dimensioned to engage in a slight interference fit therewith.

Seal bores 32, 32a extend respectively from housing inner surfaces 22, 22a inwardly to flanges 28, 28a and accommodate sealing means 33, 33a for suitably sealing the inner ends of housings 20, 20a about common shaft 14. Sealing means 33, 33a are secured in place by means of threaded seal plates 34, 34a each of which have suitable wrench adaptable heads 35 and are received in a threaded portion of bores 32, 32a. Gear 36 is securely mounted by suitable means (not shown) on

shaft 14 between the opposed housing inner surfaces 22, 22a and rotates therewith.

Opposed hollow, cylindrical power transmitting rotors 38, 38a are respectively mounted in thrust bearings 39, 39a for rotation within rotor bores 26, 26a respectively and comprises opposed cam head portions 40, 40a and shank portions 42, 42a. Shank portions 42, 42a are mounted in bearings 39, 39a and keyed by keys 43 (only one shown) to respective rotor mount portions 44, 44a of shaft 14. Nuts 45, on threaded ends 46, 46a of shaft 14, further secure power rotors 38, 38a to shaft 14 and prevent axial movement thereof within respective rotor bores 26, 26a. Accordingly, opposed rotors 38, 38a and gear 36 on shaft 14 provide an integral rotatable power transmitting element of Unit 10, opposed rotors 38, 38a respectively rotatable within bores 26, 26a and gear 36 rotatable between housing units 12, 12a.

Common drive shaft 14 has a central bore 50 therethrough, the purposes of which will become more apparent and be fully described hereinafter.

Cam head portions 40, 40a of rotors 38, 38a are identically constructed and are generally of hollow cylindrical configuration having side walls 51, 51a and end cam surfaces 52, 52a. The cam side walls with cam surfaces 52, 52a have closed, generally sinusoidal paths. As illustrated in FIG. 7 and FIG. 8, the latter showing a plane developed view of cam heads 40, 40a, cam surfaces 52, 52a each comprise respectively a pair of diametrically opposed power stroke surfaces 54, 54a and a pair of diametrically opposed return stroke surfaces 55, 55a, with intervening vertices 56, 56a and recesses 57, 57a. It will be seen from an inspection of FIGS. 1, 2, 7 and 8 that cam head portion 40a is angularly offset 90° from cam head portion 40 whereby the vertices 56 and recesses 57 of cam head 40 are respectively opposed to and in axial alignment with recesses 57a and vertices 56a of cam head 40a. The angular offset orientation of opposed cam heads 40, 40a is provided through the proper mounting and keying of rotors 38, 38a to shaft 14. Rotors 38, 38a are mutually aligned and coaxial with and have a common internal diameter to that of cylinder heads 24, 24a. Accordingly, the hollow interior of cam head portions 40, 40a permits reciprocal travel therewithin of pistons 60, 60a. Cylinder head slotted skirts 30, 30a provides additional guide means for pistons 60, 60a. It will be appreciated from inspecting FIGS. 1 and 2 that cam surfaces 52, 52a are bevelled slightly outwardly, the purpose of which will become more apparent hereinafter. Ends 61, 61a of cylinder skirts 30, 30a confronting cam surfaces 52, 52a are complementarily bevelled to the bevel of the cam surfaces. This complementarily peripheral beveling of cylindrical skirt ends 61, 61a with vertices 56, 56a of rotatable cam heads 40, 40a, see FIG. 1, facilitates smooth reciprocation and travel of respectively opposed pistons 60, 60a without both the cylinder heads and respective hollow cam head.

Power storage pistons 60, 60a are of identical construction and each uniquely consists of an outer piston element 62, 62a and an inner piston element 64, 64a: see FIG. 2. The purpose of this unique piston construction will be more fully detailed hereinafter in describing the operation of my power unit 10 as illustrated in FIGS. 1 through 8. Generally, however, power storage pistons 60, 60a are so constructed that part of the power from the initial explosive impulse caused by the

firing of the working fluid is stored by the pistons for subsequently substantially complete release during the stroke of the pistons. This unique construction reduces the sudden build up of high stresses in the piston guide means due to the initial explosive impulse, which guide means will be more fully described herein.

Outer piston elements 62, 62a, each with piston rings 65, are received and reciprocate respectively within cylinder heads 24, 24a whereby power chambers 66, 66a are provided respectively therein. From FIG. 2, it will be appreciated that each outer piston element 62, 62a is generally hollow, having coaxial cylindrical cavities 68, 68a and 69, 69a therein, which cavities are separated by centrally open flange 70, 70a. Cavities 68, 68a suitably accommodate inner piston elements 64, 64a with piston rings 71 for limited reciprocation respectively therein, much as cylinder heads 24, 24a accommodate outer piston elements 62, 62a. Springs 72, 72a are located within cavities 68, 68a and extend between inner cavity surfaces 74, 74a of inner piston elements 64, 64a and confronting surfaces 75, 75a of flanges 70, 70a. Although not necessary in a two cycle engine since the piston is continuously under some pressure, I have shown in FIGS. 2 and 5 that spring 72 is secured through brackets 76 and clamps 77 to the respective confronting surfaces 74 and 75. More particularly, end 78 of spring 72 is secured to surface 74 of inner piston 64 by means of brackets 76. Brackets 76 may be secured to surface 74 through suitable screw means (not shown) or surface 74 may be suitably constructed whereby arcuate lip means are provided under which the end 78 of spring 72 may be lodged through appropriate rotation thereof. The particular means of securing spring end 78 to surface 74 is not of primary significance herein and accordingly further detail is not believed necessary. However it will be appreciated that in assembling piston units 60, 60a springs 72, 72a are secured first to respective surfaces 74, 74a. Similarly the particular means of securing spring end 79 to flange surface 75 is not of primary significance herein and surface 75 could likewise be constructed with arcuate lip means under which end 79 may be lodged. However I particularly show, FIG. 5, the securement of spring end 79 to flange surface 75 by means of "J" clamp 77 which extend through holes 80 in flange 70 and receive threaded nuts 81 on the ends thereof against the flange surface of cavity 69. Inner piston 64a is similarly connected through spring 72a to outer piston 52a. See also FIG. 7.

Springs 72 and 72a are designed so that the normal compression of working fluid in chambers 66, 66a before respective firings will not effect relative movement between inner piston elements 64, 64a and outer piston elements 62, 62a. The construction of springs 72, 72a is such that relative movement between the respective inner and outer piston elements and accordingly compression of the springs occurs only during the initial explosive impulse caused by firings in the respective power chambers. By the time pistons 60, 60a are at the ends of their power strokes, springs 72, 72a will have returned to their normal position. Accordingly this unique piston construction reduces the sudden build up of stress in the piston pins and surfaces in contact upon chamber firings but restores to the system substantially all the initially stored energy before the end of the respective power strokes.

Each outer piston element 62, 62a includes cylindrical skirt 82, 82a, at the enlarged bottom 83, 83a of which are diametrically opposite bores 84, 84a to receive respective piston pins 85, 85a therethrough. See FIG. 2 and particularly FIG. 5. Each end 86, 86a of the pins projects from the outer surface of skirt 82, 82a and has rotatably mounted thereon generally frusto-conical cam rollers 88a and generally frusto-conical piston guide rollers 90, 90a, separated by washers 91, 91a. Piston guide rollers 90, 90a freely rotate within substantially semi-cylindrical and diametrically opposite piston guides 92, 92a which extend parallel to rotor bores 26, 26a and open thereinto.

Piston guides 92, 92a extend inwardly from housing surfaces 21, 21a longitudinally of bores 26, 26a to substantially rounded ends 93, 93a. The ends of guides 92, 92a at housing faces 21, 21a are closed by the cylinder head flanges 25, 25a. Cylinder skirts 30, 30a have diametrically opposed slots 95, 95a longitudinally in line with piston guides 92, 92a. As may be seen from FIGS. 1, 2, and 4, slots 95, 95a have semi-circular inner ends 96, 96a and are of sufficient width with complementary bevelled sides to properly accommodate respective cam rollers 88, 88a in rotation, much in the same manner that piston guides 92, 92a accommodate guide rollers 90, 90a.

As previously noted, cam surfaces 52, 52a are bevelled slightly outwardly and it will be evident from a review of FIGS. 1, 2, 3 and 7 that the beveling of cam surfaces 52, 52a is to complement the generally frusto-conical shape of cam rollers 88, 88a. The purpose of complementarily beveling of cam surfaces 52 and cam rollers 88, taking these elements by way of example only, is to substantially eliminate sliding friction between these two elements. Accordingly it will be appreciated that the shape of cam rollers 88 is generally formulated by radial lines X, Y, FIG. 5 extending from a point at the axial center of the rotor 40, and in regard to cam surface 52, the bevel at any point or possible point of contact with cam roller 88 is formulated by lines X, Y taken in a plane which includes the axis of the cam roller and the point or possible point of contact.

To further reduce the friction between cam surface 52 and cam roller 88, for example, it is possible to construct cam roller 88 with a peripheral curvature such that at any one location, it effects or could effect substantially point contact with cam surface 52, for example, point 98 shown in FIG. 5. Accordingly, with the above construction, sliding friction between the cam surface 52 and cam roller 88 is substantially eliminated and rolling friction between these elements is kept to a minimum. The same construction and relationship exists for cam roller 88a and cam surface 52a. The cam rollers 88, 88a are preferably constructed of needle bearings with the outer race being machined to the desired peripheral curvature. The cam rollers 88, 88a are of hardened steel and the cam surfaces 52, 52a are steel hardened.

Frusto-conical piston guide rollers 90, 90a as shown in FIGS. 2 through 6 are preferably of identical shape, size and construction as cam rollers 88, 88a and in co-operation with respective piston guide 92, 92a retain rollers 88, 88a on pin ends 86, 86a. Hardened steel washers 91, 91a separate rollers 88, 88a from rollers 90, 90a and it will be appreciated from the drawings, particularly FIGS. 5 and 6, that the rollers 88, 90 and

88a, and 90a are opposed or placed front to front to washers 91, 91a.

From FIGS. 3 and 6, it will be appreciated that the diameter of semi-cylindrical piston guides 92, 92a is slightly greater than the maximum diameter of guide rollers 90, 90a thereby permitting guide rollers 90, 90a to rotate freely within the guides 92, 92a upon substantially point contact between the inner surface thereof and the point of maximum diameter of the rollers, for example, point 99 (on the power stroke of piston 60) as shown in FIG. 6. It is clear from the foregoing that pistons 60, 60a are guided for reciprocal motion only, cam rollers 88 on the power stroke of piston 60 engaging diametrically opposite power stroke cam surfaces 54 and imparting rotation to rotor 38 which is transmitted to gear 36. Similarly, the power stroke of piston 60a imparts rotation to gear 36 in the same direction through cam rollers 88a engaging power stroke cam surfaces 54a of rotor 38a, see FIG. 8.

It will be appreciated that although the construction of the cam rollers, piston rollers and piston guides heretofore described is intended to reduce to a minimum the development of heat within the engine due to friction between the several engaging elements, this construction must be balanced with the desire to also keep to an acceptable level the stress developed in the several elements due to the operative contact between such elements. It will be appreciated that constant high stress will cause the various elements such as cam surfaces and piston pins to fatigue quickly. Accordingly it will be appreciated that in certain engines depending on the speed at which the engine may primarily be run, cam rollers 88, 88a may preferably be simply frusto-conical with the apex of the frustum of the cone being on the axis of the rotor thereby spreading the force of contact over the width of the complementarily bevelled cam surface 52. Likewise it will be appreciated that guide rollers 90, 90a may simply be cylindrical roller members whereby piston guides 92, 92a would assume the configuration in cross section of a rectangle.

To further reduce the development of heat within the power unit and to periodically relieve the stresses in piston guide means and rotor cam means there is provided as an important feature to my invention means for raising the cam rollers 88, 88a slightly off the respective return stroke cam surfaces of rotors 38, 38a. More particularly, it will be appreciated taking FIG. 2 for example, wherein piston 60a is at the top of its stroke whereas piston 60 is at the bottom of its stroke, that it is advantageous in relation to net power output and to preventing fatigue in pins 85, 85a to return piston 60 to the top of its stroke during the power stroke of piston 60a by means other than return stroke cam surface 55. Accordingly, it is desirable to have pistons 60, 60a connected or associated in such manner that the distance between pins 85, 85a and consequently cam rollers 88, 88a is slightly greater than the distance between the cam surfaces 52, 52a at any point of time. With this construction, the power stroke of piston 60a (wherein cam rollers 88a engage power stroke cam surfaces 54a of rotor 38a), returns piston 60 to the top of its stroke, and during this return stroke causes cam rollers 88 to be disengaged from return stroke surfaces 55 of rotor 38. The reverse is true when piston 60 is on its power stroke. This generally permits cooling of the cam rollers and cam surfaces and periodically relieves stress due to contact therebetween. Further, as the return

stroke cam surfaces are not used to cam the pistons to the top of their strokes, a cam surface profile is possible which provides a longer, straight line power stroke surface resulting in enhanced net output of each unit.

To this end then, returning to FIGS. 2, 5 and 7, pistons 60, 60a are interconnected for joint reciprocal movement by means of rods 100, 100a slidably received in shaft bore 50 and respectively connected through pin connectors 101, 101a to pins 85, 85a. Connectors 101, 101a, received in piston cavities 69, 69a, are generally of cylindrical configuration and have axial bores 102, 102a through which pins 85, 85a respectively pass. Rod ends 103, 103a are received in bores 104, 104a of connectors 101, 101a and are secured thereto by suitable means such as by welding. However it will be appreciated that with reduced threaded ends, the rods could be threadedly secured to the connectors, the reduced threaded ends permitting an appropriate shoulder joint between associated rod and connector thereby reducing the stress on the threads. Inner rod ends 105, 105a are generally flat with slight rounding about the periphery thereof.

As previously noted the combined length of rods 100, 100a is important as the distance between pins 85, 85a must be slightly greater than the distance between opposed points on cam surfaces 52, 52a at any point in time. This adjustment need only be calculated and made initially and it will be appreciated that in constructing rods 100, 100a slightly longer than required and after appropriate connection to connectors 101, 101a, the inner ends of the rods may be ground to provide the desired operative separation between the piston pins 85, 85a. It will be further appreciated that with a threaded connection between a reduced threaded end of at least one rod and a connector, which connection would be such to provide a suitable shoulder joint between the rod and connector, the rod could be selectively adjusted by shim means in assembling the engine to provide the desired operative separation of the pistons.

Suitable sealing means such as O-rings 106 seal bore 50 about rods 100, 100a thereby sealing the central portion of bore 50 from the hollow interior of rotors 38, 38a and bores 26, 26a.

As my power unit is representatively illustrated in a two cycle internal combustion engine, working fluid passages and exhaust passages are appropriately located in the housings and cylinder heads, it being appreciated that suitable valving and carburetor means (not shown) are provided to operate and control the engine in known fashion. More particularly, as shown in FIG. 1, housings 20, 20a have inlet working fluid passages 110, 110a leading from suitable valving means (not shown) into a piston guide 92, 92a and bores 26, 26a. Cylinder heads 24, 24a have inlet passages 111, 111a and exhaust ports 112, 112a and have suitable spark means 114, 114a secured in the dome thereof. Suitable lubrication means (not shown) may also be provided for the basic unit and it will be appreciated that it is common in two cycle engines to employ a fuel mixture including a lubricant therein for suitably lubricating moving parts. Rotative power output of Unit 10 is transmitted through meshing gears 36 and 115 to drive shaft 116; see FIG. 2. Gear 115 is secured to shaft 116 by suitable means (not shown) and shaft 116 is suitably supported in bushings 117, 117a which are supported by supports

118, 118a, secured by welding or other suitable means to base 15.

OPERATION OF BASIC POWER UNIT

5 Now with reference to the operation of the basic power unit shown in FIGS. 1 through 8, with particular reference being made to FIGS. 2 and 8, it should be appreciated that FIG. 8 schematically illustrates piston 60 during its power stroke while FIG. 1 illustrates piston 60 at the bottom of its power stroke. Considering more particularly FIG. 8, the opposed profiles of rotors 38, and 38a are shown separated by rotor shaft 14. Shown in dotted lines are piston guides 92, 92a, pins 85, 85a and rods 100, 100a. It will be appreciated that piston guide rollers 90, 90a are superimposed on cam rollers 88, 88a and traverse in guides 92, 92a. Rods 100, 100a interconnect piston pins 85, 85a. With piston 60 part way through its power stroke (left to right) as shown in FIG. 8, diametrically opposed cam rollers 88 engage power stroke cam surfaces 54 and cause, since piston 60 is prevented from rotation by rollers 90 and guides 92, rotor 38 to rotate as shown by the arrow thereon. Rods 100, 100a have been constructed so that during this power stroke of piston 60 they maintain, cam rollers 88a, through pins 85, 85a, slightly off return stroke cam surfaces 55a thereby permitting these rollers and surfaces to cool and relieving stress due to contact therebetween. Due to the fly wheel nature of gear 36, it will be appreciated that rollers 88 pass the bottom of recesses 57 of cam surface 52 and rollers 88a advance over vertices 56a of cam surface 52a, piston 60a compressing working fluid within chamber 66a which compressed fluid acts as a cushion for piston 60a. Accordingly, upon appropriate firing in chamber 66a piston 60a begins on its power stroke (right to left) causing the rotors and shaft 14 to further rotate as shown and maintaining through rods 100, 100a cam rollers 88 slightly off return stroke cam surfaces 55.

Considering now the operation of the engine from FIG. 2 it will be appreciated that when power chamber 66a fires piston 60 will be driven right to left. However the initial explosive impulse caused by the firing of chamber 66a will force inner piston element 64a to the left thereby compressing spring 72a and consequently reducing the sudden build up of stress in pin 85a, cam rollers 88a and power cam surfaces 54a. Any working fluid within cavity 68a is vented into bore 62a through centrally open flange 70a. As previously noted, during the remaining travel of piston 60a, spring 72a is designed to return inner piston element 64a to its normal position substantially planar with the end of outer piston 62a. The brackets 76a and clamps 77a eliminate any chance of inner piston element 64a "popping out" of outer piston element 62a at the end of the power stroke while chamber 66a is exhausting although it will be appreciated that the piston is still under slight pressure due to simultaneous incoming of fresh working fluid.

60 While piston 66a is at the top of its stroke, piston 66 is at the bottom of its stroke at which time chamber 66 is exhausting through port 112 as fresh working fluid is entering thereinto. This fluid entering the chamber 66 through passage 111 comes from within bore 26 and piston guides 40 and is under slight compression as a result of the motion of piston 60 on its previous power stroke. Bracket 77 and clamps 78 prevent any chance of piston 64 from "popping out" of cavity 68 in piston

64 due to the fluid in bore 26 and guides 40 being compressed and acting on the inner surface 74 of inner piston 64 because of axially opened flange 70 although any pressure in this regard will be less than that within the chamber 66 during a power stroke. As piston 60 proceeds on its return stroke due to the power stroke of piston 60a and rods 100, 100a, thereby covering ports 111 and 112, the working fluid in chamber 66 is compressed in readiness for firing when piston 60 approaches its top dead center position.

The design of springs 72, 72a is such that they are only compressed, that is, pistons 64, 64a have moved relatively inwardly of outer associated pistons 62, 62a, at the time of the greatest impulse within chambers 66, 66a caused by the detonation of working fluid therein. Accordingly the compression of working fluid in chambers 66, 66a does not effect the compression of respective springs 72, 72a. Moreover springs 72, 72a are so designed that they substantially resume their normal at rest condition by the time pistons 60, 60a have uncovered ports 111, 111a and 112, 112a and reached the bottoms of their respective power strokes, thus returning substantially all the energy initially stored therein to useful power during the respective power stroke.

The rotation of rotors 38, 38a and shaft 14 as a unit is transmitted to drive shaft 116 through gears 36, and 115, gear 36 acting as a fly wheel to carry the pistons over the respective top and bottom dead centers of their strokes.

Although the cam surfaces 54 have been shown with a particular slope, it will be appreciated that the slope may be varied depending on the power characteristics desired. Increasing the slope giving a longer power stroke of the pistons enhances the torque characteristics of the engine at lower speeds whereas reducing the slope, in effect, causing a shorter piston stroke, enhances speed characteristics of the engine at higher speeds. It will be appreciated that for every complete revolution of rotor shaft 14 there are 4 power strokes, two by each piston 60, 60a. Moreover, in addition to providing the uncammed return stroke of respective pistons and thereby allowing cooling of the camming element and periodically relieving stress therein, the unique provision of rods 100, 100a permits the profile of the cam surfaces and accordingly of rotors 38, 38a to exhibit relatively pointed verticies thereby attributing to the provision of longer power stroke cam surfaces and resulting in greater net power output of the power unit. As a result of the provisions of rods 100, 100a the diameter of the recesses 57, 57a of cam head portions 52, 52a may be taken as the sum of the diameter of the cam rollers 88, 88a plus the radius of the verticies 56, 56a, thereby providing for a cam profile with a maximum length of operative power stroke cam surfaces. It will also be appreciated that instead of the cam portions 40, 40a being angularly offset 90° when the guide means 92, 92a are planar, guide means 92a could be angularly offset 90° from guide means 92 with the cam head portions 40, 40a exactly in line.

Accordingly, my basic power unit provides a substantially self balanced reliable unit developing a minimum of internal heat while at the same time having good output power and torque characteristics.

ENGINE WITH A PLURALITY OF BASIC POWER UNITS

Now with reference to drawings 9 through 32, a plu-

rality of my power units are illustrated embodied in a steam engine 120.

It will be apparent from a review of these drawings that steam engine 120 as set forth herein provides for 5 the operative association of four individual basic power units A-E, B-F, C-G, and D-H peripherally located about a common and central output shaft, each of the basic units being substantially the same as the basic unit 10 illustrated in FIGS. 1 through 8. The alphabetic designation of the units in FIGS. 9 to 32 relate to an individual cylinder, piston and rotor unit and indicates to an individual cylinder, piston and rotor unit and indicates for example that unit A is in axial alignment with unit 15 E, the opposed pistons thereof being connected or otherwise associated for reciprocation in unison, thereby providing in conjunction with respective cylinders and opposed interconnected rotors, a basic power unit A-E. It will be appreciated by those skilled in the art that although I illustrate four basic units operatively associated in engine 120, this number is by way of illustration only and an engine could, without difficulty, be manufactured with more, for example, five or six or less, for example two or three than this number of basic power 20 units located in a housing about the central drive shaft. The minor modifications required to the teachings of the present embodiment to achieve such will be obvious to those skilled in this art upon a full appreciation of this specification.

25 Each of the four basic units, A-E, B-F, C-G and D-H is of substantially identical construction and their selectively controlled operation and lubrication in the steam engine is by means of valve mechanisms and a lubrication system both of which will be fully described herein.

30 Now with particular reference to FIG. 9, engine 120 includes central housing 121 including left and right transmitter housings, 122, 122a, left and right steam catches 123, 123a and left and right cylinder heads 124, 124a. It will be appreciated from an inspection of the drawings that the left side of engine 120 is substantially identical to and a mirror image of the right side thereof. The minor differences within the interior of a power unit and of the engine between the "left" side and the "right" side thereof will be pointed out herein-after in describing fully the elements thereof. Nevertheless, "left" and "right" as used herein refer to the positional relationship of similar parts as viewed in the drawings, and the "a" designates those elements to the 35 right of the engine which are similar to parts on the left thereof.

40 Housing 121 has four mounting brackets 125 with holes 126 providing means by which the engine 120 may be anchored to any suitable support (not shown).

45 Below housing 121 and secured thereto is oil pan 127 with a filler tube and cap 128, the pan 127 to be more 50 fully described herein.

55 As the basic power units A-E, B-F, C-G and D-H are substantially identical to each other and to the basic unit described previously in relation to drawings 1 through 8, it is not believed necessary to describe each unit A-E, B-F, C-G and D-H in detail as their basic construction will be obvious from the drawings and previous description. Accordingly Unit A-E herein will be taken as the exemplary unit with the understanding that the other basic units B-F, C-G and D-H are similarly constructed.

POWER TRANSMISSION OF PLURALITY OF BASIC UNITS

From an inspection of FIGS. 11 and 12, FIG. 11 showing the single power Unit A-E in section and FIG. 12 showing power unit A-E and diametrically opposite power unit C-G in section, it will be noted that left and right housings 122, 122a are substantially identical and both may be cast and machined of a suitable material such as iron. Housings 122, 122a are generally cylindrical in shape, with the exception of the area about mounting brackets 125 and have mutually engaging surfaces 130, 130a. Housings 122, 122a are secured together by eight threaded cap screws 131, the heads 132 of which engage bottom shoulder 139 of piston guides 140 in housing 122, which guides, along with piston guides 140a in right housing 122a are otherwise identical to those described previously in relation to FIGS. 1 through 8. Any suitable washer means may be used with cap screws 131 and a suitable seal may also be used between surfaces 130, 130a, as desired.

Each of the mutually engaging surfaces 130, 130a has a generally-epicycloid cavity therein which cooperate to form four generally cylindrical gear chambers 142, 143, 144, 145 substantially inscribing a common gear chamber 146; see FIG. 13. The gear chambers 142, 143, 144, 145 and 146 are associated respectively with power units A-E, B-F, C-G and D-H, and house respectively gears 147, 148, 149 and 150. Common gear chamber 146 houses gear 151 which is mounted on and keyed to a common central drive shaft 152. Gears 147 to 151 are all of identical size and accordingly it will be appreciated that one revolution of anyone of the gears 147 to 150 causes one revolution of drive shaft 152.

With reference to exemplary unit A-E which is shown in section in FIGS. 11 and 12, gear 147 is mounted on and keyed to Unit rotor shaft 154. Radially inwardly extending flanges 155, 155a separate gear chamber 142 from left and right opposed rotor bores 156, 156a. Thrust bearings 157, 157a are press fitted within bores 156, 156a to abut flanges 155, 155a respectively and respectively support opposed cylindrical power transmitting rotors 158, 158a for rotation within bores 156, 156a. Opposed power rotors 158, 158a are mounted on respective ends of rotor shaft 154 by keys 159 and nuts 160 in the same manner as the power rotors in the basic unit are mounted as described in relation to FIGS. 1 through 8. Accordingly, opposed power rotors 158, 158a and gear 147 on rotor shaft 154 provide an integral rotatable power transmitting unit for unit A-E, opposed rotor 158, 158a rotatable within bores 156, 156a respectively and gear 147 rotatable within gear chamber 142.

Unit rotor shaft 154 has a central bore 162 therethrough, the purpose of which will be obvious from the previous description but nevertheless will be further described herein.

Power rotors 156, 156a have cam head portions 163, 163a respectively, both being of identical profile as those previously described, namely rotors 40, 40a in FIGS. 1 through 8. More particularly rotors 163, 163a are angularly offset 90° to each other, have bevelled cam surfaces 164, 164a, each with two power stroke surfaces 165, 165a and two return stroke surfaces 166, 166a and are hollow to permit reciprocating travel of respective opposed pistons 168, 168a. Pistons 168, 168a are substantially identical in construction but

minor differences will be referred to hereinafter, it being appreciated that pistons 168, 168a are not power storage pistons like those previously disclosed in connection with an integral combustion engine. Pistons

5 168, 168a each comprise fluid working surfaces 169, 169a, piston rings 170, 170a and cylindrical skirts 171, 171a. It will be appreciated from inspecting FIGS. 11 and 12 that pistons 168, 168a are hollow with diametrically opposed reinforcement members 172, 172a, 10 extending from inner, generally semi-spherical dome 173, 173a to opposed skirt blocks 174, 174a. Blocks 174, 174a are each mutually bored to receive respective piston pins 175, 175a therethrough. Each end of pins 175, 175a projects from the outer surface of piston 15 skirts 171, 171a and have rotatably mounted thereon generally frusto-conical cam rollers 176, 176a and generally frusto-conical piston guide rollers 178, 178a, separated by washers 179, 179a. Piston guide rollers 178 freely rotate within substantially semicylindrical and diametrically opposite piston guides 140 and similarly piston guide rollers 178a freely rotate within like constructed guides 140a. Piston guides 140, 140a extend parallel to rotor bores 156, 156a and open thereinto. Guides 140, extend inwardly from surface 20 180 of left housing 122 and longitudinally of bore 156 to shoulder 139 against which abuts cap screw head 132, as previously described. Piston roller guides 140a extend inwardly from surface 180a of right housing 122a and longitudinally of bore 156a to a substantially rounded end 181. The ends of guides 140, 140a at housing faces 180, 180a are closed by cover plates 182, 182a respectively.

It will be appreciated that the association and cooperation between the piston guides 140, 140a and piston 35 guide rollers 178, 178a and the cam rollers 176, 176a and bevelled cam surfaces 164, 164a is identical to like elements as described and illustrated in FIGS. 1 through 8 heretofore and accordingly further detail in this regard is not believed necessary. FIG. 14, being a 40 sectional view through the steam engine shows the location of the rotor bores, rotors and the piston guides of the four basic units about drive shaft 152.

In this embodiment of a plurality of power units in a steam engine, I show by way of illustration only, FIGS. 45 11 and 12, that pistons 168, 168a are connected together for conjoint reciprocal movement by means of rod 184 and pin connectors 185, 185a. Rod 184 is slidably received in bore 162 within rotor shaft 154 and connectors 185, 185a are generally of cylindrical configuration and have a central bore 186, 186a through which passes respective piston pins 175, 175a, and bores 187, 187a perpendicular thereto. End 188a of rod 184 is located within bore 187a and fixedly secured to connector 185 by suitable means such as welding, that is, it is identically constructed as like parts previously described in basic unit 10 in FIGS. 1 through 8. However, end 189 of rod 184 is located in bore 187 and is adjustably secured to connector 185 by means of 50 double threaded screw 190 which passes in axial alignment with rod 184 through connector 185 and pin 175. The cooperating threads 181 between connector 185 and screw 190 are of greater pitch than the cooperating threads 192 between screw 190 and rod end 189 whereby the distance between pins 175 and 175a may be minutely controlled through selective rotation of screw 190. Nut 193 locks screw 190 in a selected position. Removable threaded plug 194 in the top of piston 55 60 65

168 permits the necessary tools to be inserted into the interior of piston 168 in assembling the unit in order to properly adjust screw 190 (and nut 193) and accordingly the distance between pins 175, 175a in relation to cam surfaces 164, 164a.

Any other means of adjustably connecting rod 184 to piston 168 may be used in place of the double threaded screw 190. For example, rod end 189 and screw 190 could be connected together by means of a ball-and-socket type of joint whereupon the threaded connection between connector 185 and screw 190 would be of suitable pitch to permit relatively minute control of the distance between pins 175, 175a.

It will be further appreciated that the feature of maintaining the distance between pins 175, 175a slightly greater than the fixed distance between cam surfaces 164, 164a may be accomplished by constructing both connectors in the same fashion as connectors 101, 101a shown in FIG. 2, that is, non-adjustable, but with a split rod in bore 162. In this construction no threaded plug 194 in piston 168 is necessary and the only important feature is to make sure the total length of the split rod is such that when the split ends of the rod contact each other on the return stroke of either piston, the associated cam rollers are raised slightly from the associated return stroke cam surfaces of the rotary cam. This split rod construction facilitates easier assembly of the units but an engine so constructed does not have the positive breaking effect that is present in the adjustable rod construction since the pistons in the split rod engine would assume positions at the top of their respective strokes when the working fluid is cut off.

ENGINE CYLINDERS AND STEAM CATCHES

At the outer ends of central housing 121, FIGS. 11 and 12, are peripheral flanges 196, 196a, each having a shoulder portion 197, 197a adapted to receive edges of walls 198, 198a of cylindrical steam catches 123, 123a. It will be appreciated from an inspection of FIG. 12 that in the vicinity of mounting bracket 125, shoulder portions 197, 197a become grooves 199, 199a into which fit these edges of steam catch walls 198, 198a.

Cylinder heads 124, 124a have similar peripheral shoulder portions 200, 200a about inner surfaces 201, 201a of flanges 202, 202a. Shoulder portions 200, 200a are coaxial with shoulder portions 197, 197a and are adapted to receive the other edges of steam catch walls 198, 198a.

Cylinders 204, 204a are identical for power unit A-E and the cylinders of the each power unit B-F, C-G, and D-H are similar to cylinders 204, 204a. Skirts 205, 205a of cylinders 204, 204a are dimensioned to fit within the outer end of respective rotor bores 156, 156a with a slight interference fit. Cylinders 204, 204a are mutually aligned and coaxial with and have a common internal diameter to that of cam heads 163, 163a. Ends 206, 206a of the cylinders are bevelled inwardly with substantially the same degree of bevel as that of cam surfaces 164, 164a (FIG. 5) for the same purpose as noted in describing the basic Unit 10. Cylinder skirts 205, 205a have diametrically opposed slots 207, 207a longitudinally in line with roller guides 140, 140a. Slots 207, 207a have semi-circular inner ends and are of sufficient width, with complementary bevelled sides to properly accommodate respective cam rollers 176, 176a in rotation, in the same manner as like elements

described and illustrated with respect to the basic unit 10.

Cylinders 204, 204a have peripheral shoulders 208, 208a separating skirts 205, 205a from cylinder walls 209, 209a. Shoulders 208, 208a peripherally abut through suitable seals 210, 210a (for example, of aluminum) cover plates 182, 182a adjacent circular openings therein. Cover plates 182, 182a facially abut housing surfaces 180, 180a and peripherally abut the inner surface of steam catch walls 198, 198a. Screws 212, 212a (see FIGS. 15 and 18), in addition to oil return passage nuts 213, 213a secure cover plates 180, 180a in place and it will be appreciated that cylinder shoulders 208, 208a maintain the cover plates in sealed relationship with surfaces 180, 180a about the cylinder openings in cover plates 182, 182a. FIG. 15 is generally a sectional view of the left end of the engine through line 15-15 of FIG. 10 and shows cover plate 180 split for the purposes of illustrating these structural aspects of the engine.

From FIGS. 11, 12 and 16, the latter being a sectional view through steam catch 123 in the vicinity of cylinder head 124, it will be noted that the opposite ends of cylinders 204, 204a have peripheral lips and shoulders 214, 214a, 215, 215a respectively, the lips 214, 214a being sealing received in coaxial circular grooves 216, 216a of inner surfaces 201, 201a of cylinder heads 124, 124a. Seals 217, 217a may be of suitable material such as aluminum. Cylinder heads 124, 124a are secured through steam catch walls 198, 198a to housings 122, 122a by means of cylinder head bolts 218, 218a. Accordingly, it will be appreciated that cylinders 204, 204a are securely fixed between cylinder heads 124, 124a and housings 122, 122a. Cylinders 204, 204a have steam exhaust ports 220, 220a, five being shown, in the cylinder walls 209, 209a, adjacent shoulders 208, 208a. Each of the cylinders of the other power units are similarly shown in this embodiment with five exhaust ports.

The location and orientation of the cylinders exhaust ports 220, 220a of the different power units may be seen from FIGS. 12 and 15, particularly the latter wherein cylinder walls 209 of the left end of units B-F and C-G are shown in section. Cylinders exhaust ports 220 of both units B and C as shown, extend generally radially outwardly away from central shaft 152. The exhaust ports of Units A and D, although not specifically shown in FIG. 15, extend in a manner similar to those of Units B and C namely, generally radially, outwardly away from shaft 152. From FIGS. 15 and 16 it will be noted that cylinders 204 of units A, B, C, and D are locked in proper location and orientation by means of the cooperation between seal bushing 222 which surrounds central shaft 152 through steam catch 123, and groove 223, aligned in each shoulder 208 and 215 of each cylinder 204. Bushing 222 will be further described hereinafter. Moreover, the cylinders 204 of Units E, F, G, and H are similarly located and oriented by means of seal bushing 222a and aligned grooves 223a in cylinder shoulders 208a and 215a.

Steam exhausting from exhaust ports 220, 220a and through auxiliary valve exhaust, to be described more fully herein, and any condensate, exits from steam catches 123, 123a through flanged outlets 224, 224a and may be carried via a return pipe (not shown) to a condenser (not shown) all of which will be readily appreciated by those skilled in the art.

CENTRAL DRIVE SHAFT AND CYLINDER
HEADS

As previously noted, the steam engine illustrated as a preferred embodiment includes four substantially identical basic power units A-E, B-F, C-G, and D-H housed within housing 121 and operatively controlled as an integral power engine. Common drive shaft 152 extends through central bores 226, 226a in housings 122, 122a and is suitably journaled within housing 121 by grooved journal bearings 227, 227a, which bearings are located in bores adjacent common gear chamber 146. Gear 151, as previously noted, is mounted and keyed to shaft 152 for rotation in common gear chamber 146 and meshes with gears 147-150 of power units A-E, B-F, C-G, D-H respectively; FIG. 13. Unit gears 149, 150 of Units C-G, D-H, are of lesser width than gears 147, 148 of Units A-E, A-F thereby permitting bevelled gears 228, 229 to be secured to the respective unit shafts 154 of Units C-G and D-H within respective unit gear chambers 144 and 145. Bevelled gears 228, 229 will be further described in connection with the valve advance mechanism and lubrication system. It will be appreciated however that power in and the reciprocal motion of the respective unit pistons is transformed through respective unit rotors into rotary motion which results in rotation of central shaft 152 through the unit gears 147-150 and central gear 151.

Cylinder heads 124, 124a are identical and mirror images of each other and as best seen from FIGS. 10, 17 and 28, each generally comprises circular flanges 202, 202a with outwardly raised portions 230, 230a extending therefrom, portions 230, 230a constructed so as to accommodate the heads of screws 218.

Within each cylinder head 124, 124a is a generally cylindrical valve gear chamber 232, 232a coaxial with respective flanges 202, 202a. Bores 233, 233a extending between chambers 232, 232a and respective cylinder head surfaces 201, 201a accommodate seal bushings 222, 222a which guide central shaft 152. Flanged bushing heads 234, 234a seat securely against the respective inner end walls of chambers 232, 232a and threaded ends 235, 235a are threadedly received in threaded ends of bores 226, 226a of housings 122, 122a. Notches 239, 239a in flanged heads 234, 234a permit insertion of an appropriate tool for tightening seal bushings 222, 222a into position. Fiber seals 240, 240a and O-rings 241, 241a enhance the sealing nature of bushings 222, 222a.

Chamber bores 242, 242a, outwardly of chambers 232, 232a, accommodate roller bearings 244, 244a with a slight interference fit. Bevelled gears 245, 245a are mounted on and keyed to reduced portions 246, 246a of shaft 152 for rotation within chambers 232, 232a, the shank portions of the bevelled gears being respectively mounted within bearings 244, 244a.

The ends of shaft 152 are suitably constructed to accommodate means for transferring power from shaft 152 to a particular device to be driven. By way of example, coupling flanges 248, 248a are shown and although the particular structure of mounting these flanges is not important, they are shown as mounted on and keyed to tapered portions of shaft 152 through shanks 249, 249a (FIG. 12). Threaded nuts 250 suitable secure flanges 248, 248a against axial movement. The drive flanges are shown with holes 251 to facilitate coupling where desired to any device to be driven by

engine 120 and it will be appreciated that power may be taken from either or both ends of the engine, as desired.

Circular seals 254, 254a abut bearings 244, 244a. Seal plates 255, 255a are secured by means of screws 256 to cylinder heads 124, 124a to retain bearings 244, 244a and seals 254, 254a in proper position thereby preventing lubricant oil from leaking out from chambers 232, 232a through bearings 244, 244a. Oil return bores 258, 258a extend vertically downwardly from the bottom of chambers 232, 232a and meet horizontally extending oil return passages 260, 260a. Threaded plugs 261, 261a close the bottom ends of oil return bores 258, 258a; see FIGS. 17 and 32.

VALVE MECHANISM

With further reference to cylinder heads 124, 124a in conjunction with the valve mechanism, FIGS. 11, 16, 18 and 32 illustrate each cylinder head having a main steam inlet bore 264, 264a threaded at its outer end to receive elbows 265, 265a, both of which are connected to a main steam line (not shown). Slightly oval valve inlet bores 266, 268, as seen in FIG. 17, extend diagonally downwardly from the bottom of bore 264 into respective valve sleeve bores 269, 270. In view of the similarity between the valve mechanisms in the left and right cylinder heads, it is believed sufficient to detail only that shown in the left end cylinder head 124.

Further from FIG. 17 it may be seen that slightly oval cylinder steam bores 271, 272 extend from sleeve bore 269 diagonally through cylinder flange 202 into respective cylinder chambers of units B and C whereas slightly oval cylinder steam bores 273, 274 extend from sleeve bore 270 diagonally through flange 202 into respective cylinder chambers of units A and D.

Valve exhaust bores 276, 277, 278 and 279 extend generally perpendicularly from sleeve bores 269, 270 through cylinder flange 202 into steam catch 123 (FIGS. 17, 18 and 19).

Hollow cylindrical valve sleeves 280, 281 are opposed and suitably received within respective sleeve bores 269, 270 for slight rotational movement therein. As may be seen from FIGS. 20 and 21, showing cylindrical sleeve 281, sleeve 281 has several circular ports, which ports, when sleeve 281 is in bore 270, cooperate with the several previously noted bores, namely, port 282 cooperates with inlet steam bore 268, ports 283, 284 cooperate respectively with cylinder steam bores 273, 274 and ports 285, 286 cooperate respectively with valve exhaust bores 278, 279. Sleeve 281 is retained within sleeve bore 270 by means of screw 287 which is threadedly retained in the raised outer wall 230 of sleeve bore 270 and projects into elongated slot 288 of sleeve 281 thereby permitting slight rotational movement of the sleeve within its bore (counter clockwise as seen in FIGS. 19 and 20) but preventing axial movement thereof. Reduced hollow circular portion 290 of sleeve 281, forming inner shoulder 291, extends outwardly from bore 270 when sleeve 281 is in its assembled position. It will be appreciated by reviewing FIGS. 17, 18 and 20-22 that sleeves 280, 281 are mirror images of each other and accordingly, it is not believed necessary to further detail sleeve 280. Furthermore, from a further inspection of FIG. 18, it will be appreciated that each sleeve 280a, 281a at the right end of the engine in cylinder head 124a, diagonally opposite each sleeve 280, 281, is identical to each sleeve

280, 281. Accordingly, further elaboration of the sleeves in cylinder head 124a is not believed necessary.

Returning to FIGS. 17 and 18 and in particular FIG. 17 showing in section the left cylinder head 124, opposed rotary valves 294, 295 are located within hollow sleeves 280, 281 respectively and are identical in construction. Each identical valve 294, 295 comprises bevelled gear portion 296, bearing portion 297, reduced cylindrical portion 298, cylindrical steam control portion 299 and shaft portion 300. Shaft portion 300 of valves 294, 295 extend through reduced hollow portions 290 respectively of sleeves 280, 281 and it will be appreciated that valves 294, 295 when assembled in sleeves 280, 281 are prevented from outward axial movement by inner shoulders 291. A shaft portion 300 of one of the valves may be extended for mounting a pulley thereon facilitating drive means for driving ancillary equipment where necessary such as a generator or water pump.

Bearing portion 297 and control portion 299 of each valve 294, 295 support its respective valve for rotation within their respective sleeves 280, 281 and support respective gear portions 296 for rotation within chamber 232. Gear portions 296 are in mesh with bevel gear 245 and accordingly, valves 294, 295 are positively driven by drive shaft 152. Bearing portions 297 and control portions 299 are in close peripheral proximity to the inner surface of the sleeves and act as a seal to maintain steam within steam operative portions of the respective sleeves 280, 281. Reduced cylindrical portions 298 of valves 294, 295 are located where inlet steam bores 266, 268 meet ports 282 of respective sleeves 280, 281, thereby effectively forming a circular steam channel 301 by virtue of the opposed faces of bearing portions 297 and control portions 299.

FIGS. 23 and 24 show identical valves 294, 295 and it will be appreciated from these FIGS., in conjunction with FIGS. 17 and 18, that the control portion 299 has axially extending inlet channel 304 and exhaust channel 306 cut in the peripheral surface thereof. Inlet channel 304 opens into circular steam channel 301 and it will be appreciated that the axial extent of inlet channel 304 must be such to uncover the sleeve ports (for example 283, 284) associated with cylinder steam bores 273, 274 to steam in channel 301. Exhaust channel 306 is so located in control portion 299 and is of such axial extent that the sleeve ports (for example 283, 285) associated with both cylinder steam bore and valve exhaust bore (273, 278) of the same unit are simultaneously uncovered as the valve rotates. Identical valves 308, 309 for the right end of the engine 120, namely, for use in cylinder head 124a are mirror images of valves 294, 295 and FIG. 25 shows a sectional view of valves 308, 309. A further appreciation of this mirror image relationship will be received from reviewing FIG. 18 and accordingly it is not believed necessary to further detail valves 308, 309.

A comparison of FIGS. 19, 20, and 23 will show the preferred angular relationship between the valve inlet and exhaust channels, the sleeve ports associated with the steam inlet bore and the sleeve ports associated with cylinder steam bores and valve exhaust bores. It will be appreciated that the peripheral extent of the exhaust channel of the valves is greater than that of the inlet channel as it is well known in the art that exhaust valves are controlled for opening for a period of time greater than the opening of inlet valves. The width of

the inlet channel is substantially the same as the diameter of the sleeve ports which are all of uniform size.

The steam inlet bore, for example, 268 as shown in FIG. 19, the cylinder steam bores 273, 274 and the valve exhaust bores 278, 279, are slightly oval in cross section. As may be seen from comparing FIGS. 19 and 20, the above just-mentioned bores are constructed such that even with the slight rotation of sleeve 281 in bore 270 permitted by pin and slot connection 287, 288, the ports in sleeve 281 completely vent to the associated bores. The purpose of permitting slight rotation of sleeve 281 in bore 270 and of each other sleeve in its respective bore is to provide for a valve advance mechanism. This mechanism, to be described hereinafter, simultaneously rotates each of the sleeves in its associated bores in a direction counter to the rotation of the respective valves, thereby slightly advancing the timing of the valve as speed of the engine increases. A further appreciation of this unique construction of the valves may be found upon a review of FIGS. 26 through 29 inclusive, which show schematically in section, each of the valves, the associated sleeves and the associated sleeve bores of the cylinder heads 124, 124a. Arrows "V" indicate the rotation of the valves and arrows "S" indicate the rotation of the sleeves to effectively advance the valve timing. The relative construction of various bores to the various ports of the sleeves will also be appreciated from inspection of FIGS. 26 through 29. The algebraic notations A through H indicate schematically the locations of the pistons and cylinders of Units A-H in relation to the cylinder head bores and sleeve ports of the valve mechanism.

FIG. 30 is a table illustrating the piston position and cylinder activity for the various eight Units, A-H, for every 45° of rotation of common output shaft 152 and taken in conjunction with FIGS. 26-29 illustrating the timing of the valves, it being appreciated that valves 294, 295, 308, 309 rotate 90° in the direction of arrow "V" for every 45° rotation of shaft 152 since there are two power strokes per unit for each revolution of shaft 152. Further reference will be made to FIGS. 26-30 in describing the operation of the engine.

VALVE ADVANCE MECHANISM

The mechanism for controlling valve advance is shown principally in FIGS. 9, 10, 13, 14, 18, 31, and 32 and it will be appreciated that the linkage mechanism for controlling the rotation of each of the sleeves is similar. A lever 312 is keyed by means of key 313 to each reduced end 290 of respective sleeves 280, 281, 280a, 281a and extends horizontally toward the ends of the engine as shown in FIG. 9. As seen in FIG. 10, oppositely curved links 314, 315 are pivotally connected to the ends 316 of levers 312 and secured against separation by means of cotter pins 317. Links 314, 315 are pivotally connected by pivot pins 318 to the opposite ends of a lever 320. Lever 320, as may be seen from FIGS. 10, 31 and 32, has a central hub 321 to which an end of rod 322 is fixedly secured by means of lock nut 323. It will be appreciated from the latter two figures that the links and levers at the right end of the engine are identically constructed to those of the left, and the hub 321a of lever 320a is fixedly secured to the other end of rod 322. Accordingly, rod 322 extends substantially the length of the engine 120 and is supported for rotational movement by bearings 324, 324a in the bottom raised portion 230 of the cylinder heads 124, 124a.

Pressure fit seals 325, 325a suitably retain bearings 324, 324a in place and prevent leakage of lubricant outwardly along rod 322. Rod 322 passes through the center of oil return passages 260, 260a and through oil pan 127. Bearing mounts 326, 326a, within oil pan 127 are secured to the flat bottom 327 of housing 121 and support rod 322 near the center thereof. Between bearing mounts 326, 326a and secured perpendicular to rod 322 is lever 328 having a flat, forked end 329.

As best seen in FIGS. 13, 14 and 31, the valve advance device includes a small bevelled gear 330 supported and mounted on shaft 331 for rotation within gear chamber 145 (Unit D-H), in mesh with bevelled gear 229. Shaft 331 extends downwardly through a central opening in cylindrical support element 332 which has a flange 333 detachably secured to the housing bottom 327 for retaining element 332 within bore 334 of housing 124a (see also FIG. 32). Element 332 supports thrust bearing 336 and provides support for bushing 337 which guides shaft 331. Shaft 331 extends downwardly into oil pan 127 and to its bottom end is secured circular plate 338. Plate 338 has a generally flat steel hardened upper surface 339 and is fixedly secured to shaft 331 for rotation therewith by means of key or pin 340. Above plate 338 is umbrella-like housing 342. Housing 342 houses hardened steel ball bearings 343 which rest on plate surface 339, the balls also being in contact with the inner surface of the housing 342. Shaft 331 passes through bore 344 of housing 342 which bore permits housing 342 to move vertically on shaft 331. Thrust bearing 345 is supported on top of housing 342 and is in contact with the underside of forked end 329 of lever 328, thereby permitting rotation of housing 342 relative to lever end 329. Above forked end 329 is washer 346 which, with bushing 337, confines compression spring 347 about shaft 331. As shaft 331 is driven by rotor shaft 154 of Unit D-H through bevelled gears 229 and 330, plate 338 is caused to rotate. Rotation of plate 338 causes housing 342 to rotate through contact with balls 343. Rotation of plate 338 and housing 342 containing balls 343 causes the balls to move slightly outwardly due to centrifugal force, thereby causing housing 342, due to its umbrella-like shape, to rise slightly and through thrust bearing 345 cause lever 328 to turn clockwise as shown in FIG. 13 (counter-clockwise as shown in FIG. 14). Rotation of lever 328 causes rotation of rod 322 which in turn causes rotation of levers 320, 320a in the direction as shown in FIGS. 9, 10 and 31. Rotation of levers 320, 320a causes each lever 312, through links 314, 314a, 315, 315a to rotate, as shown whereby, all valve sleeves are simultaneously rotated in a direction opposite to the direction of rotation of the associated valves. Increasing the speed of the engine advances valve timing whereas as the speed of the engine decreases, the centrifugal force acting on the balls 343 is reduced, thereby permitting housing 342 to move downwardly under the force of spring 347. Accordingly, the sleeves, through respective levers 312, links 314, 314a and 315, 315a, levers 320, 320a, rod 322 and lever 328 are caused to rotate in the opposite direction (the same direction as the associated valves), returning to their slow speed position.

LUBRICATION SYSTEM FOR ENGINE

Oil pan 127 depends from the bottom 327 of central housing 121 between flanges 196, 196a and comprises

an upper generally rectangular centrally open housing 350 and bottom plate 351. Upper inwardly extending flange 352 of housing 350 (see FIG. 31) is secured to bottom 327 by suitable screw means and plate 351 is secured to the bottom, outwardly extending flange 353 of housing 350 by means of bolts 354. Suitable seal means may be used between flange 353 and plate 351. Plug 355 is threadedly received in plate 351 and provides for oil drainage from pan 127, oil filler pipe and cap 128 providing, of course, for the addition of oil to the pan.

Gear type oil pump 356 is dependently mounted within oil pan 127 from housing bottom 327 by means of brackets 358 and suitable screw means. Pump 356 is driven via bevel gears 228 and 359, gear 228, as previously noted, being mounted and secured to rotor shaft 154 of unit C-G adjacent gear 149. Bevel gear 359 is supported by means of shaft 360 extending upwardly from oil pump 356, which shaft is rotatably guided by bushing means (not shown) within pump extension 361. Extension 361 is located within bore 362 in housing 132a (FIG. 31) and also contains a thrust bearing (not shown) for suitably taking up thrust along the shaft caused by the engagement of bevelled gears 228 and 359.

In order to show other components and the conduits of the lubrication system it is thought sufficient to trace the flow of oil through the system and accordingly the engine. Oil in oil pan 127 passes through filter 364 of oil pump 356 and is pumped via conduits 366 and 367a (FIG. 31) into vertical oil bores 368, 368a in respective housings 122, 122a, conduits 366 and 367 being suitably secured to oil bores 368 and 368a respectively. Oil in bores 368, 368a passes upwardly into grooved bushings 327, 327a and flows along shaft 152 inwardly into central gear chamber 146 and outwardly along shaft 152 in bores 226, 226a. Oil flowing outwardly along shaft 152 passes between the shaft and seal bushings 222, 222a and into cylinder head chambers 232, 232a. This oil lubricates gears 245, 245a, valve gear portions 296, 296a, valve bearing portions 297, 297a and bearings 244, 244a and flows downwardly out of chambers 232, 232a through vertical oil bores 258, 258a additionally lubricating bearings 324, 324a supporting rod 322 in cylinder heads 124, 124a. Oil return passages 260, 260a return this oil to oil pan 127.

Passages 260, 260a are identically constructed and include tubes 370, 370a threadedly secured at ends 371, 371a to cylinder heads 124, 124a and extending through steam catches 123, 123a to be slidably received at their outer ends in oil return passage nuts 213, 213a. Nuts 213, 213a are threadedly secured in holes 372, 372a of flanges 196, 196a and O-rings 374, 374a between tubes 370, 370a and the inner bore of nuts 213, 213a prevent intermixing of steam and oil and the leaking of one fluid into the other.

Oil passing around drive shaft 152 in the grooves of bushings 227, 227a is forced upwardly through conduits 376, 376a in housings 122, 122a, splitting at the top thereof to flow horizontally along conduits 378, 380 in housing 122 and conduits 378a, 380a in housing 122a. Oil passes through oil nozzles 382, 382a in the ends of conduits 378, 380 and 378a and 380a into the most upwardly directed piston guides 140, 140a of units A-E and B-F (see FIGS. 11, 13, 14 and 32). Oil forced from nozzles 382, 382a lubricates the moving parts within rotor bores 156, 156a of the upper units

A-E and B-F with the motion of the pistons 168, 168a causing some oil to pass along rod 184 in bore 162 thereby lubricating these elements. In addition, oil lubricates the inner peripheral surface of the rotor bores and flows behind rotors 172, 172a through thrust bearings 157, 157a into the respective unit gear chambers 142 and 143 of units A-E and B-F. It will be further appreciated from FIG. 11 that oil in rotor bores 156, 156a also lubricates the cylinder walls as oil entering cylinder skirt slots 207, 207a is caught by the lower most piston ring of pistons 168, 168a when they are respectively at the bottom of their strokes.

Oil in rotor bores 156, 156a of units A-F and B-F flows out at the lower most piston guide slots 140, 140a through slots 384 and 385 and 384a and 385a which are cut in the surfaces 180, 180a of housings 122, 122a and covered by cover plates 182, 182a; see FIG. 15. Oil flows into the upper piston guides 140, 140a and rotor bores 156, 156a of the lower units C-G and D-H and lubricates all moving parts therein and in addition lubricates the cylinder walls and the thrust bearings of these units in the manner as noted above for Units A-E, B-F. Oil in the rotor bores of units C-G and D-H flows out of these units through joint slots 386, 386a in the surfaces 180, 180a of housings 122, 122a, adjacent the lower most piston guides 140, 140a of these units as seen in FIG. 15. This oil returns to oil pan 127 through oil passages 387, 387a in housing flanges 196, 196a. In addition oil flows out of the inner ends of the lower-most piston guides 140, 140a of units C-G and D-H through vertical holes 388, 389 and 388a, 389a in the housings 122, 122a into oil pan 127; see FIGS. 14, 31 and 32.

Oil flowing inwardly into individual unit gear chambers 142-145 and oil flowing inwardly into central gear chambers 146 lubricates the meshing of unit gears 147-150 with central gear 151. This oil flows downwardly into the bottom of gear chambers 144, 145 of units C-G and D-F and lubricates the bevelled gears 228, 359 and 229, 330. In addition this oil also lubricates the shafts 360 and 331 and associated bushings and thrust bearings of the oil pump and valve advance mechanism. Moreover oil in gear chambers 144, 145 also returns to pan 127 through bores 391, 392 in housing 122 which bores extend from the bottom of chambers 144, respectively. As noted previously, oil in chambers 232, 232a provide lubrication for bearing portions 297 of the valves 294, 295, 308, 309, the oil working behind gear portions 296 to provide a film of lubrication about portions 297. Exhaust steam from the cylinders, which includes in dispersion small oil particles from the oil lubricating the cylinders, provides lubrication for valve control portions 299 of the valves.

OPERATION

Having described in detail the structure of the preferred embodiment of my power unit and its embodiment in a steam engine, I now set forth the operation thereof although it is believed that persons skilled in this art will have already appreciated the operation of my invention. In order to assist in understanding its operation, arrows have been used in several Figures to show the direction of movement of rotation of moving elements. Steam from a boiler (not shown) is directed through a control valve (not shown) to inlet bores 264, 264a through elbows 265, 265a and enters steam bores 266, 268, in cylinder head 124 and bores 266a, 268a

in cylinder head 124a (see FIGS. 17, 18 & 32). Accordingly steam is continuously maintained in circular channels 301 of respective valves 294, 295, 308, 309.

As may be seen from FIGS. 26 - 29 which schematically represent the valve mechanisms, noting the alphabetic designation of the cylinder units and the arrowed direction of rotation of the sleeves (to advance timing) and the valves, Units C and E are about to fire, their respective pistons being at the top of their strokes and the valve inlet channels 304 approaching the respective sleeve ports cooperative with the cylinder steam bores of these units. Accordingly, pistons of units G and A, being connected by rod 184 for reciprocation in unison therewith are at the bottom of their strokes whereat respective cylinder ports 220, 220a are uncovered. The steam or working fluid has accordingly been exhausted from the cylinders of units G and A and only a residual amount may remain due to exhaust back pressure. From FIGS. 26 and 29, it will be seen that the exhaust channels 306 of valves 295 and 309 have just reached the cylinder steam ports and exhaust ports of these units and accordingly Units G and A will valve exhaust while Units C and E are firing.

Considering now Units B-F and D-H as shown in the drawings and particularly FIGS. 26 - 29, units B and H have just received steam and accordingly are under pressure approximately half way through their respective power strokes. Units F and D, connected to units B and H respectively are accordingly valve exhausting the residual steam as their pistons proceed on their return strokes. The valve exhausting is actually auxilliary to the cylinder port exhausting and permits reduced clearance between the pistons and cylinders. It will be appreciated that cylinder exhausting of the steam enhances the efficiency of the engine as each unit and the engine as a whole is basically a uniflow system. The valves 294, 295 and 308, 309 are positively driven by the drive shaft 152 and in a rotative direction wherein the valve exhaust channels 306 lead the valve inlet channels 304. FIG. 14 illustrates a sectional view through housing 122 and the units A, B, C and D. The piston of unit A is at the bottom of its stroke while that of unit C is at the top of its stroke. The piston of unit B is on its power stroke and accordingly moving away from the viewer whereas the piston of unit D is on its return stroke and accordingly moving toward the viewer. The direction of rotation of the rotors of each unit A, B, C and D is shown by arrows and that of shaft 152 is also shown. Steam exhausting from the cylinders through cylinder exhaust ports 220, 220a and through the valve exhaust channels 306 into steam catches 123, 123a exits from the engine (along with any condensate) through outlets 224, 224a, returning to the over-all system in known fashion. It will be appreciated that with the steam or working fluid controlled in this manner, each piston is reciprocated in its respective cylinder in a timed sequence, with those pistons which are under power effecting the return of the pistons connected or associated therewith. As previously noted, rods 184 are adjusted to or constructed of such a length that the cam rollers of a returning piston are raised slightly off and are disengaged from the return stroke cam surfaces of the associated rotor cam surfaces. With the flow of lubricant through the rotor bores, the lubricant and disengagement effect and permit cooling of the power contact surfaces. In addition rods 184 permit a cam head and cam surface profile of the rotors which en-

hances power output since the vertices of the profile may be relatively pointed permitting a longer and substantially straight line power stroke cam surface.

Relative valve positioning is shown in FIGS. 18, 19 and 26 through 29 whereas the activity in the cylinders of respective units A to H inclusive and the valve timing is shown in the Table of FIG. 30. FIG. 30 illustrates the simultaneous firing of two pistons every 45° of rotation of output shaft 152 which firing pistons and diagonally opposite to each other in the engine, for example, unit C fires simultaneously with unit E and as units G and A are interconnected respectively with units C and E, the activity of units A and G is identical, that is, cylinder port exhausting (See FIGS. 26-29 and the first column of FIG. 30). Likewise the activity of each unit at anyone point in time with this valve setting is the same as that of the unit diagonally opposite it in the engine. For example, units B and H are both under power simultaneously whereas units D and F are both valve exhausting. Accordingly, for every revolution of output shaft 152 there are 16 power strokes, two by each of the units A through H. With power transmitted from the pistons to the axially aligned unit rotors which are peripherally located about and geared to output shaft 152, there is provided a smooth running, self balanced engine with good power output characteristics.

It will be appreciated that with 16 power strokes per revolution of output shaft 152, the gear ratio of the valves may be selected and they may be assembled in their respective sleeves such that there is provided a single unit firing every 22 1/2° of rotation of the output shaft 152. For example, the firing order would be A, G, B, H, C, E, D, F, A, G, B, H, C, E, D, F, a firing every 22 1/2° interval of rotation of output shaft 152 with two firings per unit per revolution of shaft 152.

As previously noted the flow of steam to the engine bores 264, 264a is controlled by a control valve means between the engine and the steam supply. The engine is capable of running smoothly at low speeds without a significant advance to the valve timing. However as the quantity of steam to the engine is increased thereby causing an increase in speed of the engine, the valve advance mechanism ensures advancement of the valve timing to provide continuous smooth engine operation. The advance mechanism is positively driven off the rotor shaft of unit D-E and it will be appreciated that an increase in the speed of the engine causes the speed of rotation of the housing-plate assembly (342, 338) of the advance mechanism to likewise increase thereby operatively causing the housing 342 to rise as a result of the outward movement of the bearing balls 343 under the influence of centrifugal force. The upward movement of the housing 342 operatively causes through the previously described movement of the several levers, rods and linkages, the simultaneous rotation of all valve sleeves counter to the rotation of their respective valves. The ports of the sleeves are accordingly peripherally shifted, each, however, remaining in direct communication with its respective oval bore in the cylinder heads, the major axis of each oval bore (at least adjacent to its respective sleeve port) being perpendicular to the axis of the sleeves. Decrease in speed of the engine through reducing the quantity of steam flowing thereto will reduce the valve advance by rotating the sleeves in the direction of rotation of the associated valve. Rotation of the sleeves is limited by the pin and slot connections 287, 288.

It will be further appreciated that the lubrication system as previously described provides for the lubrication of all moving and rotating elements within each gear chamber and rotor bore in the engine.

Accordingly, I have described heretofore my invention in preferred forms, as adaptable in a simple internal combustion engine and as adaptable in numbers in a steam engine, but while the description of my preferred forms has been in detail, it will be appreciated that several modifications may be made to the specific apparatus without departing from the spirit of my invention as defined in the appended claims.

The embodiments of the invention in which an exclusive property or privilege is claimed are defined as follows:

1. In a power unit having a cylinder and a piston received for reciprocation therein and a drive shaft, means in axial alignment with said piston member for transforming reciprocal motion of said piston member into rotary motion of said drive shaft, said means comprising a hollow cylindrical rotor connected at one end to said drive shaft and having at its other end annular cam surface means coaxial with said piston member, said piston member being slidably receivable within said rotor at said other end, means guiding said piston member for reciprocation within said cylinder and said rotor and cam means on said piston member operatively engaging said cam surface means to transform reciprocal motion of said piston member into rotary motion of said drive shaft.

2. The power unit of claim 1 including a housing having a cylindrical bore, said rotor being mounted in said housing for rotation in said bore, said piston guide means comprising diametrically opposed pin means extending from said piston member, diametrically opposed slot means in said housing adjacent to and longitudinally parallel to said bore, and roller means rotatably mounted on each pin means and receivable for rotation in said slot means.

3. The power unit of claim 2 wherein said piston cam means includes cam roller means rotatably mounted on said piston pin means intermediate said piston and said guide roller means, washer means on said pin means separating said cam rollers and guide rollers and said cam roller means operatively engaging said rotor cam surface means to transform reciprocal motion of said piston member into rotary motion of said drive shaft.

4. The power unit of claim 3 wherein said rotor cam surface means comprises an endless sinusoidal track peripherally located between said piston member and said rotor bore, said track having two diametrically opposed power stroke cam surfaces and two diametrically opposed return stroke cam surfaces with intervening recesses and vertices between adjacent power stroke surfaces and return stroke cam surfaces whereby said opposed cam roller means engage said cam surfaces transforming reciprocal motion of said piston into rotary motion of said drive shaft.

5. The power unit of claim 4 wherein said cam roller means are of generally frusto-conical shape, said cam surfaces being beveled outwardly, complementarily to said cam roller means whereby substantially rolling contact exists between said cam roller means and cam surfaces.

6. The power unit of claim 5 wherein said cam roller means have a peripheral curvature whereby the contact between said beveled cam surfaces and cam roller

means is substantially rolling point contact, said guide roller means being substantially of identical size and shape to said cam rollers and mounted on said pin means in confronting relationship thereto, said slot means being generally semi-circular in cross section and of such a radius whereby said roller guide means are received for rotation therein and effect substantially rolling point contact therewith.

7. In a power unit having opposed first and second axially aligned cylinder and piston assemblies wherein said pistons are reciprocal in said cylinders, means in axial alignment with and intermediate said assemblies for transforming reciprocal motion of each piston into rotary motion, said means comprising a drive shaft having opposed first and second rotor means secured to each shaft end, said first and second rotor means each comprising a hollow, cylindrical member having endless cam surface means, each piston being slidably receivable within its respective rotor and means guiding each of said pistons for reciprocal motion within its associated cylinder and rotor means, means associated with said first and second pistons whereby said pistons are caused to reciprocate in unison, said pistons each having cam means operatively engaging associated cam surface means whereby reciprocal motion of each piston is transformed into rotary motion of said drive shaft.

8. The power unit of claim 7 wherein said first and second cam surface means each comprise two power stroke cam surfaces and two return stroke cam surfaces with intervening vertices and recesses, said rotor means and cam surfaces being angularly off-set substantially 90° whereby the vertices of said first cam surface are axially aligned with the recesses of said second cam surface means, said means associated with said first and second pistons being constructed whereby a power stroke of one of said pistons causing rotation of said drive shaft effects a return stroke of the other of said pistons and maintains the cam means of said other of said pistons substantially disengaged from the return stroke cam surface of its operatively associated rotor means during said return stroke.

9. The power unit of claim 8 wherein said drive shaft has an axial bore therethrough, said means associated with said first and second pistons including first and second rod means connected to respective pistons and slidably received within said bore, said first and second rod means in contact with each other within said bore whereby said pistons are caused to reciprocate in unison, and the combined length of said first and second rod means maintaining the cam means of a piston on its return stroke substantially disengaged from the return stroke cam surfaces of its operatively associated rotor.

10. The power unit of claim 8 wherein said drive shaft has an axial bore therethrough, said means associated with said first and second pistons including adjustable rod means interconnecting said pistons and slidably received within said bore whereby said pistons are caused to reciprocate in unison, and the length of said rod means being adjusted whereby the cam means of a piston on its return stroke is maintained substantially disengaged from the return stroke cam surfaces of its operatively associated rotor.

11. The power unit of claim 9 including opposed first and second housings each having cylindrical bores and diametrically opposed slot means adjacent and axially parallel to said respective bores, said first and second

rotor means mounted in said housing for rotation in respective first and second bores, said piston guide means of said first and second pistons including diametrically opposed pin means extending from said pistons and receivable in said diametrically opposed slot means in the respective housings, said slot means in the first housing being in axial alignment with the slot means in said second housing, said guide means further including rollers rotatably mounted on each said pin means and receivable in said slot means, said first and second piston cam means including cam rollers rotatably mounted on said pin means intermediate respective pistons and said guide rollers, and each said cam rollers being of frusto-conical shape and said first and second cam surfaces being complementarily bevelled to said cam rollers.

12. The power unit of claim 7 wherein said first and second cam surface means each comprise two power stroke cam surfaces and two return stroke cam surfaces with intervening vertices and recesses, the vertices and recesses of said first cam surface means being axially aligned with the vertices and recesses of said second cam surface means, said first piston cam means being angularly offset substantially 90° from said second piston cam means, said rod means being of such length whereby a power stroke of one of said pistons, transformed into rotary motion of said drive shaft through the power stroke cam surface of the operatively associated rotor means, effects the return stroke of the other of said pistons and maintains the cam means of said other piston substantially disengaged from the return stroke cam surface of the rotor means operatively associated therewith.

13. The power unit of claim 12 including first and second housings having cylindrical bores for containing said first and second rotors, said piston guide means of said first and second pistons each including diametrically opposed pin means extending from said piston and receivable in diametrically opposed slot means in the respective housings, said slot means in the first housing being angularly offset substantially 90° from the slots in said second housing, said piston guide means including guide rollers rotatably mounted on each pin means and receivable in said slot means, said first and second piston cam means including cam rollers rotatably mounted on said pin means intermediate respective said piston and guide rollers, and each of said cam rollers being of frusto-conical shape and each of said first and second cam surface means being bevelled complementarily to said cam rollers.

14. In an engine having housing means, and opposed cylinder head means secured to opposite ends of said housing, an output drive shaft rotatably mounted within and extending axially through said housing means and cylinder head means, a plurality of power units contained within said housing means and cylinder head means and circumscribing and axially parallel to said output shaft, each of said power units having a pair of opposed, axially aligned cylinder and piston assemblies and having means mounted for rotation within said housing intermediate said opposed assemblies and operatively associated with said opposed pistons for transforming reciprocal motion of each piston into rotary motion of said means, said means including opposed hollow, cylindrical rotor means connected to opposite ends of a unit shaft and rotatably mounted in said housing in axial alignment with said opposed piston and cylinder assemblies, each said rotor means hav-

ing annular cam surface means and each piston of each assembly being slidably receivable within its associated rotor means, means for guiding each piston for reciprocation within its associated cylinder and rotor means, means associated with each pair of opposed unit pistons for causing reciprocation thereof in unison, means in said housing for coupling each of said unit shafts to said output shaft, and valving means in each of said cylinder heads for controlling the flow of working fluid through the cylinders, and cam means on each piston operatively engaging the cam surface means of its associated rotor means whereby reciprocal motion of each piston in valve controlled sequence is transformed into rotary motion of said output drive shaft.

15. The engine of claim 14 wherein each said unit shaft has an axial bore therethrough, said means associated with each pair of pistons in a unit including rod means connected to each piston and slidably received within said bore, the length of said rod means being such whereby a power stroke of one of said pair of pistons effects a return stroke of the opposed piston of said pair and maintains the cam means of said opposed piston disengaged from the cam surfaces of its operatively associated rotor means during said return stroke.

16. The engine of claim 15 wherein said rod means comprises a rod connected to each of said opposed pistons in a power unit, each rod slidably received within said bore and the ends of said rods within said bore in contact with each other, and the combined length of said rods being such to maintain disengagement between the piston cam means of a piston on its return stroke and the cam surface means of its operatively associated rotor means.

17. The engine of claim 15 wherein said rod means comprises a rod interconnecting said pair of opposed pistons of each unit, at least one end of said rod being adjustably connected to one of said pair of opposed pistons, and removable means in the top of that piston permitting selective adjustment of the separation between said opposed pistons.

18. The engine of claim 14 wherein the opposed rotor means for each unit are rotatably mounted within cylindrical rotor bores in said housing, said piston guide means for each piston including diametrically opposed pin means extending from each piston and diametrically opposed slot means in said housing adjacent each rotor bore and longitudinally parallel therewith, the slot means of each power unit being planar and perpendicular to a radial line between said output drive shaft and said power unit, and guide rollers rotatably mounted on each said pin means and receivable for rotation in an associated slot means.

19. The engine of claim 18 wherein said rotor cam surface means in each power unit comprises two power stroke cam surfaces and two return stroke cam surfaces with intervening vertices and recesses, said unit rotors and respective cam surfaces being angularly offset substantially 90° whereby the vertices of the cam surface means of one of said pistons in a unit are axially aligned with the recesses of the cam surface means of the other of said pistons in the unit, and said means associated with said pistons for causing their reciprocation in unison being of such length whereby a power stroke of each one of said pistons in said units, causing rotation of said respective unit shaft, effects a return stroke of the other of each of said pistons in said units and maintains the piston cam means of said other of said pistons

substantially disengaged from the return stroke cam surface of its operatively associated rotor means during said return stroke.

20. The engine of claim 19 wherein said piston cam means include cam rollers rotatably mounted on said pin means intermediate said piston and guide rollers, washer means on each said pin means separating each cam roller from each said guide roller, and said cam rollers operatively engaging said power stroke cam surfaces to transform controlled reciprocal movement of each piston into rotary motion of its associated unit shaft.

21. The engine of claim 14 wherein said valving means includes valve sleeves rotatable within bores in said cylinder heads, and rotary valves rotatably received in said sleeves and operatively driven by said output shaft, a valve advance mechanism including means operatively driven by said output shaft and responsive to an increase in the rotative speed thereof to simultaneously rotate each of said sleeves within said cylinder head valve bores in a direction counter to the direction of rotation of said associated rotary valve to advance valve timing.

22. The engine of claim 21 having four power units circumscribing said output shaft, a valving means in each cylinder head for each of two power units and said valve advance mechanism including means below said housing operatively connected to said output shaft, said means being continuously rotated with rotation of said output shaft and including means responsive to centrifugal force for simultaneously effecting valve advance of each of said valving means through linkage means between said valve advance rotating means and respective valve sleeves.

23. The engine of claim 14 in combination with a lubrication system, said system including an oil reservoir and pump mounted below said housing, said pump being operatively driven by said engine, said lubrication system further including first conduit means extending upwardly through said housing and about said output drive shaft for carrying lubricant from said pump to said output drive shaft and the uppermost power units in said engine, second conduit means between said uppermost power units and the lowermost power units and third conduit means between said lowermost power units and said reservoir whereby lubricant is provided to reciprocating and rotating elements within said housing bore, means about said output drive shaft for conducting lubricant from said first conduit means along said output shaft to said cylinder heads for lubrication of the valving means contained therein, and fourth conduit means in said cylinder heads and housing for returning lubricant for said valving means to said reservoir.

24. The engine of claim 23 having four power units circumscribing said output shaft and peripherally spaced thereabout, two of said four units being horizontally planar and comprising the uppermost power units and two of said units, each vertically below one of said uppermost units, comprising the lowermost units, said means coupling said unit shafts of said power units to said output shaft comprising gear means secured to and mounted for rotation with respective shafts in gear chamber means within the center of said housing, said first conduit means including substantially vertical and horizontal passages in said housing on either side of said gear chamber means, said vertical

passages extending upwardly in said housing between said vertically aligned power units and about said output drive shaft and said horizontal passages extending from upper closed ends of each of said vertical conduits into an upper part of said uppermost units adjacent the respective rotor bores thereof, said second conduit means including substantially vertical passages between said vertically aligned power units, and said third conduit means including passages from a bottom part of each said lowermost units adjacent the rotor bores thereof, said passages extending through said housing into said oil reservoir.

25. The engine of claim 24 wherein said piston guide means for each unit comprises diametrically opposed slot means in said housing adjacent and longitudinally parallel to the rotor bore in each unit, diametrically opposed pin means on each piston of said units and guide rollers rotatably mounted on said pin means and receivable for rotation in said slot means, the slot means of each power unit being planar and perpendicular to a radial line between said output drive shaft and said power shaft, and each of the passages of said first, second and third conduit means leading into and out of said units adjacent the slot means associated therewith.

26. The engine of claim 18 further including working fluid exhaust catch means intermediate the ends of said housing means and respective cylinder head means, said engine having four power units circumscribing said output shaft and said coupling means between each unit shaft and said output drive shaft comprising gear means, said unit gears each having a 1:1 ratio with said drive shaft gear, a valving means each cylinder head for each of two piston units, each said valving means including a rotary valve mounted for rotation in valve bores in said cylinder head means and comprising a gear portion and working fluid control portion, a valve drive gear secured to said output shaft within each cylinder head means and in mesh with the valve gear portions of associated valves for positive drive thereof, working fluid passages to said rotary valves, inlet and

5 exhaust channels in said working fluid control portion of said valves, and passages between said valve bores and associated cylinders and between said bores and said exhaust catch means, whereby rotation of said valves controls the flow of working fluid through said assemblies.

10 27. The engine of claim 26 wherein the mesh between said valve drive gears and said valve gear portions and consequently the timed sequence of rotation of the valves is such to provide a simultaneous firing of diagonally opposed cylinder and piston assemblies very 45° of rotation of said output drive shaft.

15 28. The engine of claim 26 wherein the mesh between said valve drive gears and said valve gear portions and consequently the timed sequence of rotation of the valves is such to provide a single firing of a cylinder and piston assembly every 22 1/2° of rotation of said output drive shaft.

20 29. The power unit of claim 10 including opposed first and second housings each having cylindrical bores and diametrically opposed slot means adjacent and axially parallel to said respective bores, said first and second rotor means mounted in said housing for rotation in respective first and second bores, said piston guide means of said first and second pistons including diametrically opposed pin means extending from said pistons and receivable in said diametrically opposed slot means in the respective housings, said slot means in the first housing being in axial alignment with the slot means in said second housing, said guide means further including rollers rotatably mounted on each said pin means and receivable in said slot means, said first and second piston cam means including cam rollers rotatably mounted on said pin means intermediate respective pistons and said guide rollers, and each said cam rollers being of frusto-conical shape and said first and second cam surfaces being complementarily bevelled to said cam rollers.
